CLAIM

The ornamental design for a book-shaped teether, as shown and described.

DESCRIPTION

FIG. 1 is a top perspective view of a book-shaped teether, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in the drawings depict elements on the book-shaped teether that form no part of the claimed design.
